[57] **CLAIM**

The ornamental design for a combined optical viewing enhancer and support for a computer monitor, as shown and described.

DESCRIPTION

FIG. 1 is a front perspective view of an combined optical viewing enhancer and support for computer monitor showing my new design, on a reduced scale, with the broken line drawing of a computer monitor being for illustrative purposes only and forming no part of the claimed design;

FIG. 2 is an exploded side view in elevation of the optical element support for computer monitors of FIG. 1;

FIG. 3 is a front view in elevation of the optical element support for computer monitors of FIG. 1;

FIG. 4 is a top view in plan of the optical element support for computer monitors of FIG. 1;

FIG. 5 is a rear view in elevation of the optical element support for computer monitors of FIG. 1;

FIG. 6 is a bottom view in plan of the optical element support for computer monitors of FIG. 1; and,

FIG. 7 is a rear perspective view of a combined optical viewing enhancer and support for a computer monitor, on a reduced scale, the viewing enhancer is shown broken away for ease of illustration.

FIG. 1

FIG. 2

FIG. 3

FIG. 4

FIG. 5

FIG. 6

FIG. 7
